UNITED STATES PATENT OFFICE

RALPH M. HEINTZ, OF PALO ALTO, CALIFORNIA, ASSIGNOR TO HEINTZ & KAUFMAN, LTD., OF SAN FRANCISCO, CALIFORNIA, A CORPORATION OF NEVADA

DESIGN FOR A PORTABLE ELECTRIC GENERATOR

Application filed February 25, 1933. Serial No. 47,312. Term of patent 14 years.

To all whom it may concern:

Be it known, that I, RALPH M. HEINTZ, a citizen of the United States of America, and resident of Palo Alto, county of Santa Clara, State of California, have invented a new, original, and ornamental Design for a Portable Electric Generator, of which the following is a specification, reference being had to the accompanying drawing, forming part thereof.

The figure is a perspective view of the generator, a portion of the handle on the left-

hand side of the figure being broken away for convenience of illustration. The opposite side of the device is not shown as the entire rear face is flat, having no bearing bosses thereon.

I claim:

The ornamental design for a portable electric generator, as shown and described.

In testimony whereof, I have hereunto set my hand.

RALPH M. HEINTZ.
